Alphonse La Fon

By Attorneys,
Fraser Turner Myers

UNITED STATES PATENT OFFICE.

ALPHONSE LA FON, OF NEWARK, NEW JERSEY.

IRONING PAD.

Application filed November 11, 1922. Serial No. 600,230.

To all whom it may concern:

Be it known that I, ALPHONSE LA FON, a citizen of the United States of America, residing at Number 40 Chestnut Street, Newark, in the county of Essex and State of New Jersey, have invented certain new and useful Improvements in Ironing Pads, of which the following is a specification.

This invention relates to ironing pads or 10 the like, and aims to provide improvements therein.

The invention provides an ironing pad 15 which may be placed upon an ironing board and on to which a hot iron may be slid without necessitating that the iron be lifted from the ironing board, thereby facilitating the action of placing the iron on the pad and relieving the operator of the labor of lifting the iron each time that it is desired 20 to momentarily lay aside the iron.

The invention further provides a device 25 which may be made of light sheet metal, without the heat of the iron heating the pad in such manner as to burn or scorch the padding of the ironing board on which the ironing pad rests.

The invention further provides a device 30 which is very simple in construction and consequently may be cheaply manufactured and readily assembled.

An embodiment of the invention is illustrated in the accompanying drawings, wherein—

Figure 1 is a top plan view of the ironing pad showing it applied to an ironing board.

Fig. 2 is a cross-sectional view on the line II—II, Fig. 1.

Fig. 3 is a cross-sectional view on the line III—III, Fig. 1.

Referring to said drawings, numeral 10 designates the part or portion of the ironing pad on which a hot iron is to rest, and 11 designates a skid or lip which is adapted to fit close to or substantially flush with the surface of the ironing board, and on which skid an iron is adapted to be slid from the surface of the ironing board on to the holding portion 10. This skid or lip 11, therefore, allows the iron to be placed upon the ironing pad by the simple operation of sliding the iron along the ironing board surface, and up said lip or skid 11 on to said holding portion 10, without the necessity of having to lift said iron in order to place it on said ironing pad. The lip or skid 11 is preferably provided with a down-turned

edge portion 13, which enables the skid to depress or sink itself into the ironing board padding, thereby assuring that the iron will not be impeded in passing on to said lip or skid.

The portion 10 is conveniently made of light sheet metal, and is conveniently provided with a plurality of bosses or projections 15, preferably struck up from the sheet metal, as indicated in Fig. 3. These bosses or projections 15 are, moreover, preferably tapered in such manner that the surface of the hot iron makes only a limited contact with the projections 15, preferably 70 a point contact, and makes no direct contact with the other parts of the portion 10. This insures a considerable air space between the bottom of the hot iron and the greater part of the metal of which the portion 10 is 75 made, and, moreover, the heat conducted through the projections 15 is greatly dispersed by the time it reaches the base of the projections.

An upturned flange 17 is conveniently 80 formed around one or more sides of the holding portion 10, as indicated at 17.

A sheet of insulating material 20, such as asbestos, is preferably placed beneath the top or iron holding portion 10. 85

There is also preferably provided a lower or bottom piece or sheet of metal 22, and this bottom piece 22 is attached to the top piece 10 with the sheet of insulation 20 in between, the connection between the top and 90 bottom pieces 10 and 22 being preferably along one side of the device, as indicated at 24, in such manner that the pieces 10 and 22 may readily separate at the other edges or sides. In fact, the bottom piece 22 is 95 conveniently curved, as indicated at 26, in such manner that the top and bottom pieces 10 and 22 may separate when the top piece is not pressed down on the bottom piece, by the weight of an iron on the ironing board. 100 This enables the top and bottom pieces to separate when the ironing pad is not in use, thereby providing ready access of air between the pieces 10 and 22 for cooling.

The bottom piece 22 is conveniently connected to the top piece by means of ears 28, 29 turned down over the edge of said top piece 10, and the insulating sheet 20 is preferably interposed between connected parts of the top and bottom pieces 10 and 22, and 110 between the lugs 28 and 29 and said top piece 10, in such manner that said top piece

is entirely insulated from the bottom piece by said sheet of insulating material 20. The bottom piece 22 is also preferably provided with a turned-over edge or flange 31, which clamps the edge of the insulating sheet 20 and thereby fastens said insulating sheet to said bottom piece 22.

The skid or lip 11 is also conveniently formed as a part of said bottom sheet 22, 10 and conveniently has a depression 33 into which the adjacent edge 34 of the top piece 10 is pressed, so that said edge 34 is below the level of the adjacent portion of the skid 11, thereby readily enabling an iron to pass 15 over said edge 24 of the top piece 10.

Means are preferably provided for fastening the ironing pad to an ironing board. These means are preferably a string or tape 35, which may be passed around the edges of 20 the ironing board and the ends tied under said ironing board. Friction of the iron in sliding up said skid and on to said holding portion 10, will ordinarily displace said holder toward the end of the ironing board, 25 and this displacement will cause the string or tape to bind more tightly on the edges of the ironing board, and after the holding means or string 35 has been thus tightened, further movement of the ironing pad is prevented. The string 35 conveniently passes 30 between the top and bottom plates 10 and

22, the bottom plate 22 being conveniently provided with a lateral depression 37 for receiving said string or tape.

The inventive idea may receive other mechanical expressions than that herein specifically illustrated and described.

What is claimed is:

1. An ironing pad comprising a metal top piece adapted to hold a hot iron, a metal bottom piece, and a sheet of insulating material between said top piece and said bottom piece, said bottom and top pieces being fastened along one side and being free at their other sides to separate to allow ready access of air to the space between said pieces. 40

2. An ironing pad comprising a metal top piece adapted to hold a hot iron, a metal bottom piece, and a sheet of insulating material between said top piece and said bottom piece, said bottom and top pieces being fastened along one side and being free at their other sides to separate to allow ready access of air to the space between said pieces, 50 one of said pieces being flexible and bent away from the other at its free edge, whereby said pieces may be pressed together by the weight of the iron, and separate when the iron is removed.

In witness whereof, I have hereunto signed my name.

ALPHONSE LA FON.
